UNITED STATES PATENT OFFICE.

ALEXANDER C. BEECH, OF CHICAGO, ILLINOIS, ASSIGNOR TO KROEHLER MFG. CO., OF NAPERVILLE, ILLINOIS, A CORPORATION OF ILLINOIS.

ADJUSTABLE ARMCHAIR.

Application filed May 14, 1924. Serial No. 713,115.

This invention relates to improvements in reclining chairs, and more particularly to chairs in which the seat and back portion may be tilted at different angles to suit the convenience of the individual, or to afford a more comfortable sitting posture.

The object of the invention is to provide a reclining or tiltable chair, which can be easily operated by a person from a sitting posture, and without undue exertion, to tilt the seat and back to the desired position.

A further object of the invention is to provide a simple, yet effective, adjusting device, whereby the tilting of the seat is accomplished by shifting the movable arms, connected with frictional adjusting members, which hold the movable parts in any position of adjustment.

In the accompanying drawings I have illustrated a preferred embodiment of the invention wherein—

Figure 1 is a view in side elevation of the chair with the operating parts exposed.

Figure 2 is a view in front elevation of the chair, with portions shown in sections.

Figure 3 is an enlarged detail view of the slideable operating arm.

Figure 4 is a perspective view of the rocking lever for operating the frictional release.

Figure 5 is an enlarged detail view in elevation showing the supporting trunnions and frictional release.

Figure 6 is a perspective view of the side arm with the supporting trunnion fixed thereto, and

Figure 7 is a perspective view of the movable section of the trunnion with the operating parts connected therewith.

As illustrative of the further embodiment of the invention, a plain and substantial type of reclining chair has been shown, and consisting generally of a frame A and the rotatable or tilting seat portion B supported in the frame. The frame is made up of vertical legs 1, side frame members 2—2, extending between the front and rear legs on both sides of the frame, a cross member 3 connecting the rear legs and side arms 4—4. The seat portion B is a unitary member made up of a back 5 and a seat 6, the latter preferably extended downwardly and forwardly toward the floor and provided at its lower end with an upturned foot rest 7.

The entire seat portion B is rotatably or

tiltably supported on two trunnions located 55 on either side of the chair frame, the parts thereof being supported and forming a part of and supported by the side frame members 2—2.

The construction of the trunnions will 60 now be described. As clearly shown in Figures 1 and 5, there is formed at the junction of the back and seat 5 and 6 of the seat portion B and in a vertical plane of the side margins thereof is a rounded enlargement 8 having a circular opening or bearing 8^a formed therein, said opening being of comparatively large diameter of say 8 to 10 inches in a chair of the average size. The side frame members 2—2 are also 70 provided with upwardly projecting semi-circular projections 9—9 which lie just outside of the rounded portions 8—8 of the seat B with the curvilinear edges thereof substantially concentric with the centers of 75 the circular openings 8—8. Secured to the inner faces of the side frame members 2—2 are semi-circular shaped blocks 10 having their curvilinear faces arranged concentrically to the rounded portions 9—9 of the 80 side frame members and spaced radially inwardly therefrom and concentrically thereto as shown in Figure 6. These blocks are securely held in place by screws 11—11. Moreover, these blocks extend into the openings 8^a—8^a of the seat B, and form bearings 85 or trunnions for the seat, engaging substantially the upper half of the faces of said openings 8^a. In this manner it will be seen that the seat B is supported or suspended 90 on the blocks 10—10 and free to rotate about a horizontal axis coinciding with the centers of the bearings 8^a, 8^a.

Additional means, however, are provided for frictionally locking the seat against free 95 rotation on the trunnion blocks 10—10 and located in the lower portion of the annular bearings 8^a, 8^a are friction blocks 12, 12, being of the same shape as the trunnion blocks 10—10, both of which will be observed are 100 slightly less than true semi-circles since their straight margins are spaced apart and on opposite sides of the true center of rotation, a distance sufficient to permit a limited relative movement in a vertical direction, and to 105 allow for the introduction of springs about to be described. The blocks 10 and 12 of each trunnion are connected together and

held against relatively rotated movement by pairs of dowel pins 13—13 sunk in the upper edge of each friction block 12 and extending into sockets 10^a, 10^a bored in the lower edge 5 of each block 10. Surrounding these dowel pins are helical compression springs 14 which are normally held under compression and act to force the blocks apart, and since the trunnion blocks 10—10 are stationary the 10 action of the springs is to force the movable blocks 12, 12 downwardly against their seats in the lower half of the annular bearings 8^a.

It is manifest that in the absence of means 15 for displacing the movable frictional blocks 12, 12, vertically and against the action of the springs 14, 14, that the seat B would be held against movement relative to the chair frame, and in any position of adjustment. Moreover, the diameter of the annular bearings 8^a and blocks 10 and 12 is such as to 20 afford ample frictional resistance to the shifting of the weight of the person sitting in the chair regardless of the posture assumed.

25 In the side frame members 2, 2, and extending vertically downward and centrally from the upper edges of the rounded extensions 9, 9, are cut slots 15 which extend a short distance below the lower extremities of 30 the bearings 8^a. At the upper end of each slot 15, 15, and on opposite sides thereof the material is cut back to form right angle notches which together form a seat 16 serving the purpose presently to be pointed out. 35 Fitting within each of the vertical slots 15, 15 and adapted for limited vertical movement therein are bars 17, 17, which are permanently secured at their lower ends to the movable friction blocks 12, 12, by means of 40 screws 17^a as clearly shown in Figure 7. In the upper end of each bar 17 is mortised one leaf of a hinged connecting member 18 having its opposite or upper leaf mortised into 45 the underside of a lever block 19. As clearly shown in Figure 5, the lever block 19 stands upright in the seat 16 at the entrance of each slot 15. Moreover, the lever block 19 projects above the seat in which it rests and is 50 engaged by the manual operating member by which the adjustment or tilting of the seat is accomplished by the sitter from a sitting or reclining position.

55 Referring to Figures 1 and 2 it will be observed that the arms, 4, 4, consist of two parts, namely,—a fixed bar 20 extending between the upper ends of the legs and a movable bar 21 which substantially encloses the fixed bar 20, the two parts being mortised together so that the movable bar completely surrounds the fixed bar. As clearly 60 shown in Figure 2, the arms 4, 4, extend just above the trunnions so that by providing a slot 20^a in the fixed bar 20, the upper portion or head of the lever blocks 19, extends through the bar 20 and engages a socket or

seat 21^a in the underside of the movable bar 21 (Figures 3 and 5).

As before explained, the seat B is held against rotatable adjustment by the expansion of the trunnion blocks 10 and 12 actuated by the springs 14, 14. It follows, therefore, that the same condition will exist so long as the frictional blocks 12, 12 are not displaced. Moreover, the trunnion blocks remain in locked position when the lever 75 blocks 19, 19 are fully seated in the notched seat 16 (Figure 1). Assuming, therefore, that a person sitting in the chair in upright position as shown in Figure 1, desires to tilt backward to a reclining position, he grasps the movable bars 21 of the arms 4 and by bracing himself against the back 5 as one would naturally do, in tilting backward, he moves the bars 21 forwardly, thereby tilting the lever blocks 19, 19 on their forward edges 80 as shown in Figure 5, thereby displacing the bars 17 upwardly and releases the frictional blocks 12, 12. In this way the seat B is allowed to tilt backward until the desired 85 position is obtained whereupon the sitter releases his grasp upon the arms of the chair releasing the friction blocks 12, 12, which instantly frictionally lock the seat in the desired position. Manifestly, to again tilt the 90 seat to another position the forward pressure upon the arms is again applied, thus releasing the frictional blocks and the sitter shifting his weight forwardly, brings the seat 95 forward. Thus, it will be seen that in a 100 chair of this character the tilting or adjustment of the seat to any position is accomplished entirely by the sitter from a sitting posture and without assistance of the feet as is required in the ordinary forms of swivel chairs or even rocking chairs. All of the 105 effort is due to forward pressure upon the arms of the chair and is applied in a most natural manner by merely bracing one's self 110 against the back of the chair.

The advantage of this construction is that 110 the chair may be tilted to any desired angle and frictionally held in such position until the friction is released. A still further advantage of such a construction lies in the extreme simplicity of parts which permits it to be incorporated at a low cost in reclining chairs, thereby making it available to a 115 large class of users.

Having described the preferred embodiment of the invention, I claim:

1. In a chair of the character described, the combination of a frame and a seat 125 tiltably suspended in said frame by means of trunnions located at the sides of said frame above the center of gravity of said seat and comprising annular bearing blocks mounted on said frame and annular bearing surfaces on said seat and trunnions, and friction members yieldingly engaging said bearing surfaces and acting to increase the frictional 130

resistance of said trunnions to the tilting of the seat as the weight supported therein is shifted.

2. In a chair of the character described, the combination of a frame and a seat tiltably suspended in said frame by means of trunnions on opposite sides of said chair and each comprising an external annular bearing member of relatively large radius mounted on said seat and an internal bearing member mounted on said frame and frictionally supporting said seat throughout the upper portion thereof, said internal bearing member having an adjustable section bearing downwardly on said external bearing member, tension means acting on said adjustable section, and manually operative means for controlling the friction exerted by said adjustable section on said external bearing member.

3. In a chair of the character described, the combination of a frame and seat tiltably suspended in said frame by means of trunnions comprising vertically arranged annular bearing blocks mounted on said frame and annular bearing surfaces surrounding said blocks and integral with said seat, a section of said blocks being relatively adjustable to increase and decrease the frictional resistance between said blocks and bearing surfaces, springs acting on said adjustable section to increase the friction and manually operative means for decreasing the friction.

35 4. In a chair of the character described, the combination of a frame and a seat tiltable in said frame by means of trunnions, comprising circular bearing surfaces on said seat, circular bearing blocks mounted on said frame and frictionally engaging said bearing means, said blocks consisting of fixed and adjustable sections, springs interposed between said sections to maintain a predetermined frictional contact against said bearing surfaces and means manually operative from sitting position and connected with said adjustable section for decreasing the frictional contact with said bearing surfaces.

50 5. In a chair of the character described, the combination of a frame, a seat tiltably mounted in said frame through the medium of laterally disposed trunnions comprising annular bearing members fixed to said seat, pairs of substantially semi-circular and relatively expansible bearing blocks engaging within said bearing members, springs acting

normally to expand said blocks, and endwise movable members forming the arms of said frame and operatively connected with said blocks to control the frictional contact between said blocks and said bearing members.

6. In a chair of the character described, the combination of a frame, a seat tiltably mounted in said frame through the medium of laterally disposed trunnions comprising annular bearing members fixed to said seat, pairs of substantially semi-circular and relatively expansible bearing blocks engaging within said bearing members, compression springs acting normally to expand said blocks, a lever operatively connected with one of said blocks and endwise movable members forming the arms of said frame, and connected with said lever for manually releasing said blocks from frictional locking contact with said bearing members.

7. In a chair of the character described, the combination of a frame provided with arms having endwise sliding portions, a seat supported in said frame, by means of trunnions, on opposite sides of the chair, each comprising an annular bearing member, and spring expanded bearing blocks engaging said bearing member, a bar connected with one of said blocks, a lever hinged to said bar and mounted for rocking movement on said frame, and operatively connected with the endwise sliding portions of said arms.

8. In a chair of the character described, the combination of a frame, a seat mounted in said frame through the medium of laterally disposed trunnions, one of said trunnions comprising an annular bearing member fixed to said seat, a substantially semi-circular bearing block fixed to said frame, and engaging the upper portion of said bearing member, a relatively movable block engaging the lower portion of said bearing member, a compression spring interposed between said blocks, an endwise movable bar connected with said movable block, a rocking lever seated adjacent each trunnion and connected with each bar, said frame comprising an endwise shiftable arm, engaging said levers whereby the shifting of said arm in one direction effects the release of said movable blocks from frictional engagement with said bearing member.

Signed at Chicago, Ill., this 2nd day of May, 1924.

ALEXANDER C. BEECH.
